ATTORNEY.

UNITED STATES PATENT OFFICE.

HENRY H. DREYER, OF NEW YORK, N. Y.

DESIGN FOR A SIGN-BOARD.

SPECIFICATION forming part of Design No. 24,505, dated July 23, 1895.

Application filed May 18, 1895. Serial No. 549,836. Term of patent 7 years.

To all whom it may concern:

Be it known that I, HENRY H. DREYER, a citizen of the United States, residing at the city of New York, in the county and State of New York, have invented and produced a new and original Design for an Advertising-Sign, of which the following is a specification, reference being had to the accompanying drawing, forming part thereof, and showing an advertising-sign bearing my design.

The leading feature of my design consists in the shape of the sign-body and the surface ornamentation arranged thereon, as represented in the drawing.

In the drawing, A designates the body of the sign, the same being in the form of a parallelogram. Upon the surface of this parallelogram is a circular seal-like figure B, hav-

ing a D-shaped ornamentation superimposed thereon. Upon the surface of this parallelogram various notices or inscriptions may then be painted or printed, the representation of the circular seal-like figure forming an ornate background therefor which harmonizes with the remainder of the design. 25

What I claim is—

The design for a sign board, substantially as herein shown and described.

Signed at the city of New York, in the county and State of New York, this 15th day 30 of May, 1895.

HENRY H. DREYER.
